BARTHolemew ROY, OF ST. CLAIR, MICHIGAN.

Letters Patent No. 86,865, dated February 9, 1869.

IMPROVEMENT IN SASH-ELEVATOR AND FASTENER.

The Schedule referred to in these Letters Patent and making part of the same.

To whom it may concern:

Be it known that I, BARTHolemew ROY, of St. Clair, in the county of St. Clair, and State of Michigan, have invented a new and useful Improvement in Sash-Elevators and Fasteners; and I do declare that the following is a true and accurate description thereof, reference being had to the accompanying drawings, and to the letters of reference marked thereon, and being a part of this specification.

This invention relates to properly-constructed spring-levers and catches, attached to the upper sash of a window, by means of which the sash, upper and lower, may be raised or lowered at pleasure, and fasten them in any desired position.

The invention consists of the spring-lever A, attached, at its upper extremity, to the upper part of the sash B, and provided, at its lower extremity, with a pin, C, or a catch, or any other suitable device, to engage with any proper holes, H, in the sash D, or with a rack, E, upon the stile of said sash, by means of which the position of the two sashes, B and D, relatively to each other, is governed.

It consists, also, of another spring-lever, F, fastened, in a similar manner, to the spring-lever A, and provided upon its side, and near its lower extremity, with catch or projection G, which engages with proper holes, I, in the side of the window-frame J, by means of which the position of sashes relative to the frame J is determined, and by which they are fastened in any desired position.

What I claim as my invention, and desire to secure by Letters Patent, is—

1. The spring-lever A, when constructed, attached, and operating substantially as and for the purpose herein set forth.
2. In combination with the above, the spring-lever F, when constructed, attached; and operating as and for the purposes herein described.

B. ROY.
